UNITED STATES PATENT OFFICE.

WILLIAM EDWARD GOODYEAR, OF NEWARK, NEW JERSEY.

STOP-MOTION FOR HIGH-SPEED MACHINES.

No. 818,159.

Specification of Letters Patent.

Patented April 17, 1906.

Application filed May 27, 1905. Serial No. 262,551.

To all whom it may concern:

Be it known that I, WILLIAM EDWARD GOODYEAR, a subject of the King of Great Britain, and a resident of Newark, county of Essex, State of New Jersey, have invented a certain new and useful Improvement in Stop-Motions for High-Speed Machines, of which the following is a specification.

The object I have in view is the production of a stop-motion for high-speed machines which will positively stop the mechanism at a predetermined position and without shock.

The invention is intended for use in connection with sewing-machines, and particularly buttonhole-sewing machines, which must be stopped in a certain and definite position. The invention, however, may be applied to other forms of machinery, as is found desirable.

I attain the objects of my invention by the mechanism illustrated in the accompanying drawings, in which—

Figure 1 is a side elevation of a sewing-machine fitted with the stop-motion embodying my invention. Fig. 2 is an end view thereof, the parts being in the stop or locked position. Figs. 3 and 4 are portions of the same mechanism illustrated in Figs. 1 and 2 and showing the parts in the position they assume when the sewing-machine is running at full speed. Figs. 5 and 6 are similar views showing the parts in the position they assume when the sewing-machine is running at reduced speed. Fig. 7 is an enlarged side view for the purpose of more clearly showing the details of construction of the mechanism. Fig. 8 is a section on the lines 8 8 of Fig. 7; and Fig. 9 is a view similar to Fig. 7, but seen from the other side. Fig. 10 is a detailed view of the driving-pulleys and internal gears, taken on the sectional lines 10 10 of Fig. 11. Fig. 11 is a transverse section taken on the lines 11 11 of Fig. 10. Fig. 12 is a side elevation of a portion of the mechanism, showing a modification; and Fig. 13 is a sectional view taken on the lines 13 13 of Fig. 12.

In all of the views like parts are designated by the same reference characters.

I will describe my invention as applied to a buttonhole-sewing machine; but it is to be expressly understood that this especial embodiment is solely for purposes of illustration.

The machine illustrated is similar to that disclosed in the patent to E. B. Allen, No. 785,061, patented March 14, 1905, with the exception of the stop-motion. It is to be

understood that the illustration of this particular sewing-machine is solely for the purpose of describing the invention, as the invention of the stop-motion may be applied to any other form of sewing-machine or to any machine to which the stop-motion may be used with advantage.

In Fig. 1 the main shaft of the sewing-machine is shown in dotted lines and indicated by the character 1. The shaft is driven by the belt 2 by means of the two pulleys 3 and 4. A cam 5, carried by a disk 6, which is turned by the machine and which makes one revolution while a buttonhole is being completed, is provided. This cam is designed to engage with mechanism for shifting the belt from one pulley to the other and applying the stop-motion.

The construction of the two pulleys is illustrated in Figs. 10 and 11. The pulley 3 is loosely mounted upon a sleeve 7, which is turned with the shaft 1 by being keyed thereto by the pin 8. A collar 9 prevents the pulley from moving sidewise. The second pulley 4 is loosely journaled upon the shaft 1 and is retained in place by means of a screw 10. The sleeve 7 is provided with a flange 11, carrying studs 12. Upon these studs are mounted pinions 13 and 14, two sets of pinions being illustrated. The pinions are secured together so as to rotate at the same speed, and they bear a certain relation as to size as may be desired. As shown in the drawings, each of the pinions 14 is nearly twice the size of the pinions 13. The pinions 13 mesh with an internal gear 15, secured to the pulley 3, and the pinions 14 mesh with a pinion 16, carried by the hub of the pulley 4. The periphery of the pulley 4 is provided with a groove 17 and has formed upon it one wall of a groove 18, the other wall of the groove 18 being formed upon the pulley 3. The two grooves are of the same diameter, so that a single belt may be shifted from one groove to the other as required.

The collar 9 is provided with a finger 19, (see Fig. 8,) and this finger may be engaged with a notch 20, carried by an arm 21, when the latter is moved within the sphere of rotation of the finger. The arm 21 is pivoted at 22 and has a depending finger 23 and an arm 24. The arm 24 connects through a chain or cord 25 to the pedal (not shown) for starting the stop-motion. The finger 23 is provided with a notch on its depending extremity, forming the two steps 26 and 27. The finger

23 is adapted to be engaged with a second finger or stop 28, carried by a shaft 29. Upon the shaft 29 is a third finger 30, which is adapted to be engaged by the cam 5 and the shaft 29 oscillated and the finger 28 moved to engage with either of the stops 26 27, as desired.

A strong spring 31 depresses the finger 23 and normally tends to force the arm 21 inward and cause the notch 20 to engage with the stop 19 unless it is otherwise prevented. Carried by the arm 21 is a pin 32, which engages with a slot 33, formed in a belt-shift lever 34. The slot 33 is shaped, as shown in Fig. 7, with a vertical portion and an inclined portion, as shown. The pin 32 engaging within the slot by its reciprocation and owing to the configuration of the slot will move the belt-shift lever in such a manner as to shift the belt from one pulley to the other.

The pulley 3 is provided with a cylindrical extension 35, constituting a drum with which a brake-shoe 36 may be caused to engage. This shoe is carried by a brake-arm 37, pivoted at 38 to the sewing-machine. Carried upon this arm is a stout leaf-spring 39, the said spring being secured to the arm by suitable means, such as bolts 40, by which it will be rigidly secured thereto and will cause it to move in sequence with the spring. The free end of the spring 39 is curved at 41 outward and then is sharply bent in at 42, forming an angular portion 43. This spring is adapted to be engaged by a roller or pin 44, carried by the arm 21. Upon the arm 21 being moved outward the roller 44 will be caused to engage with the spring 39, moving it upward and forcing the brake-shoe into contact with the drum 35. The spring 39 permits elastic connection between the roller 44 and the brake-shoe. The brake-shoe is disengaged from contact with the drum by gravity.

Instead of the brake-shoe and drum (illustrated in Figs. 7, 8, and 9) a pawl and ratchet similar to that illustrated in Figs. 12 and 13 may be employed. In this modification the arm 37 is provided with a sharp point 45, constituting a pawl, and the drum 35 is provided with teeth 46, constituting a ratchet. By this construction the action of the pawl and ratchet will be more certain than the brake-shoe previously described. In Fig. 12 the pulleys 3 and 4 are shown as adapted for use with a flat belt instead of the round one illustrated in connection with the other views. The peripheries of the two pulleys are nearly flat, so that the belt will properly engage with them.

The operation of the complete device is as follows: The belt 2 is normally engaged with the pulley 4 and is presumed to be constantly moving. The parts before the starting in operation of the sewing-machine are in the position shown in Figs. 1 and 2. The finger 30 will be supported upon the cam 5, and the

finger 28 will be disengaged from the finger 23. The projection 19 will be engaged with the notch 20, and the roller 44 will be engaged with the spring 39 in front of the inclined portion 42, which will permit the brake-shoe 36 or the pawl 45, whichever is used, to be disengaged from contact with the drum 35 or ratchet 46, thus permitting the pulley 3 to rotate. The pulley 4 being turned constantly in one direction will turn the pinion 16 in the same direction, and the latter meshing with the pinions 14 will have a tendency to turn them in the opposite direction. These pinions being connected to the pinions 13 will turn them in the same direction, and the pinions 13 meshing with the internal gear 15 will turn it in the same direction or opposite to the direction of rotation of the pinion 16. The result will be that the pulleys 4 and 3 will rotate in opposite directions and the sleeve 7 will remain stationary and the main shaft 1 will not revolve. Upon the pedal being depressed through the agency of the cord or chain 25 the lever 24 will be depressed, the arm 21 retracted, and the notch 20 disengaged from the projection 19. The movement of the pin 32 within the slot 33 will oscillate the belt-shifting lever 34 and shift the belt to the groove 18, formed between the pulleys 3 and 4. The belt will engage equally on both sides of the groove 18, tending to turn both pulleys in the same direction. The pulley 3, with the internal gear 15, will tend to rotate the pinion 13 in the opposite direction, the pinion 13 turning the pinion 14 at the same rate of speed and meshing with the pinion 16 will tend to turn that in the opposite direction. The pinion 16, however, being carried by the pulley 4 will be rotated at the same speed and in the same direction as the pulley 3. Consequently the pinions 13 and 14 will be bodily turned in the same direction as the two pulleys 3 and 4. The pinions being carried by the studs 12, which are mounted upon the sleeve 7, will rotate that in the same direction and with it the shaft 1. The engagement of the roller 44 with the inclined portion 42 of the spring 39 will elevate the brake-arm 37 and cause the brake-shoe 36 or pawl 45, as depends upon the character of the machine, to momentarily engage with the drum 35 or ratchet 46, stopping such drum for an instant, as the lever 24 is being depressed and the lever 21 moved away from the collar 9 to the disengaged position. As soon as the roller 44 rides over the point of the bent portion 42 of the spring 39 and engages with the inclined portion 43 the brake-shoe or pawl will be disengaged from the drum or ratchet. The parts will be engaged together a length of time, however, to stop the pulley 3. The result of this action will be to slowly start the shaft 1. This action is as follows: The pulley 4 being turned con-

stantly in one direction will turn the pinion 16 in the same direction. Such pinion meshing with the pinion 14 will have a tendency to turn it in the opposite direction. The pinion 14 being connected to the pinion 13 will turn it in the same direction, and such pinion meshing with the internal gear will tend to turn it and the pulley 3 in the same direction or in a direction opposite to the pulley 4. The pulley 3 being prevented from rotating at this point by the action of the brake or pawl, the pinions 13 will turn upon the internal gear 15, which is temporarily stationary. The result will be that the sleeve 7, which carries the pinions, will be rotated in the same direction as the pulley 4, but at a much less rate of speed. As shown in Figs. 10 and 11, the parts are so proportioned as to rotate the sleeve 7 at about one-quarter of the rate of speed of the pulley 4; but this ratio may be varied as desired. This will start the machine and will cause it to turn the disk 6 in the direction of the arrow, allowing the finger 30 to drop from engagement with the cam 5 and permitting the finger 28 to engage with the free end of the finger 23 and rest upon the steps 26. The parts will now be in the position shown in Figs. 3 and 4. They will continue to move and actuate the sewing-machine at a maximum speed until the disk 6 has made nearly a complete revolution. As soon as the lower portion of the cam 5 engages with the finger 30 it will elevate it a sufficient distance to cause the finger 28 to become disengaged from the step 26 and fall into the step 27. This will move the pin 32 down the inclined portion of the slot 33, actuating the belt-shifter and moving the belt from the groove 18 to the groove 17. At the same time the roller 44 engages with the inclined portion 43 of the spring 39 and will oscillate the latter and raise the arm 37, causing the brake-shoe 36 or pawl 45 to engage with the drum 35 or ratchet 46. This will stop the movement of the pulley 3. The belt being in the groove 17 of the pulley 4, the latter will be rotated at the same rate of speed as before and in the same direction. This through the intermediary of the pinion 16, small gears 14 and 13, and internal gear 15, which is now stationary, will tend to rotate the sleeve 7 at a slow rate of speed and in the same direction as before, as has already been described. The shaft 1 will now be rotated at about one-quarter of its normal speed and will continue to rotate a certain definite number of revolutions until the disk 6 so moves the cam 5 as to cause the finger 30 to engage with the second incline and be elevated. This will disengage the finger 28 from the step 27 and permit the finger 23 to drop downward, this movement being assisted by means of the spring 31. The pin 32, sliding within the vertical portion of the slot 33, will not move the belt-shifter; but the arm 21, carry-

ing the notch 20, will move in the path of the projection 19 and upon the collar 9, making a complete revolution. The projection will engage with the notch and the collar and shaft will be definitely and positively stopped. At the same time the roller 44 will slip by the angular portion 42 of the spring 39 and engage beyond the inclined surface 41, permitting the lever 37 to drop and disengage the brake-shoe or pawl with the drum 35 or ratchet. This will permit the pulley 3 to then rotate, which it will continue to do in the opposite direction from the pulley 4, the pinions 13 and 14 revolving idly and the sleeve 7 remaining stationary. By this means the machine may be gradually started and positively stopped; but before stopping its speed will be reduced so that the action of stopping will be without shock.

The mechanism may be modified as desired, so as to make it applicable to other machinery in which stop-motions are of use.

Having described my invention, what I claim as new, and desire to secure by Letters Patent, is—

1. A stop-motion, wherein means are employed for automatically reducing the speed of the machine before stopping it, such means being controlled by the machine, and means for positively driving it at a reduced speed to a predetermined stopping position.

2. A stop-motion, wherein means are employed to automatically reduce the speed of the machine before stopping it, and to continue the engagement of the driving power after the speed is reduced, such means being controlled by the machine.

3. In a stop-motion, the combination with a driven shaft, of means for driving the shaft at high speed, means for positively and automatically driving the shaft at a reduced speed, such means being controlled by the driven shaft, and means for positively stopping the shaft.

4. In a stop-motion, the combination with a driven shaft, of means for positively driving the shaft at high speed, of means for positively and automatically driving the shaft at a reduced speed, to a predetermined stopping position, such means being controlled by the driven shaft, and means for positively stopping the shaft.

5. In a stop-motion, the combination with a driven member, of means for positively driving the member at high speed, such means being disengageable, of means for stopping the driven member, such means comprising means for automatically operating the driven member at a reduced speed, such means being controlled by the driven member, and means for positively stopping the driven member.

6. In a stop-motion, the combination with a driven member, means for driving the member at high speed, and a positive stop,

and means for automatically driving the driven member at a reduced speed, such means being controlled by the driven member, and means for applying the stop after the driven member has been moved to a predetermined stopping position.

7. A stop-motion having means for automatically reducing the speed of a machine a predetermined number of revolutions before stopping it, and to positively drive the machine a predetermined number of revolutions after the speed is reduced.

8. A stop-motion having means to automatically reduce the speed of a sewing-machine, after making a predetermined group of stitches, and to continue the engagement of the driving power after the speed is reduced.

9. In a stop-motion, the combination with a driven shaft, a stop therefor, a plurality of driving-pulleys, a single belt therefor, gearing between the driving-pulleys and the shaft, and means for shifting the belt and applying the stop, whereby the speed of the shaft will be reduced, and it will be positively driven at such reduced speed.

10. In a stop-motion, the combination with mechanism to drive a machine at different speeds, the said mechanism being self-contained within the driving-pulleys, and means for positively stopping the machine.

11. In a stop-motion, the combination with a shaft and a plurality of pulleys thereon, gearing located within the pulleys, and means for positively rotating the shaft at a reduced speed, and means for positively stopping the shaft.

12. In a stop-motion, the combination with a driven shaft, two pulleys thereon, gearing connecting the pulleys and the shaft, a belt, and means for causing the belt to engage with one pulley, or with both pulleys, and means for stopping the shaft.

13. In a stop-motion, the combination with a driven shaft, a sleeve thereon, pinions carried by the sleeve, a plurality of pulleys turning upon the shaft, and carrying-gears engaging with the pinions, means for rotating the pulleys, and means for stopping one of said pulleys, and means for preventing rotation of the shaft.

14. In a stop-motion, the combination with a shaft, two pulleys thereon, the said pulleys turning loosely upon the shaft, gears upon the pulleys, a sleeve upon the shaft and rotating therewith, pinions carried by the sleeve and engaging with the gears upon the pulleys, means for rotating the pulleys, means for preventing rotation of one of the pulleys, and means for preventing rotation of the shaft.

15. In a stop-motion, the combination with a shaft, a plurality of pulleys thereon, positive gearing connecting the pulleys to the shaft, means for rotating the pulleys, means

for preventing rotation of one of the pulleys, and means for preventing rotation of the shaft.

16. In a stop-motion, the combination with a shaft, two pulleys thereon, gearing connecting the pulleys to the shaft, means for driving one or both of the pulleys, means for preventing rotation of one of the pulleys, and means for preventing rotation of the shaft.

17. In a stop-motion, the combination with a shaft, two pulleys thereon, gearing connecting the pulleys to the shaft, a belt, means for causing the belt to engage with one pulley or both pulleys, means for preventing rotation of one of the pulleys, and means for preventing rotation of the shaft.

18. In a stop-motion, the combination with a shaft, a sleeve thereon, two pinions of different sizes carried by the sleeve, two pulleys turning freely upon the shaft and carrying gears engaging with the pinions, means for preventing rotation of one of the pulleys and means for driving one or both of the pulleys and means for preventing rotation of the shaft.

19. In a stop-motion, the combination with a shaft, a sleeve thereon and rotating therewith, the said sleeve carrying a large and a small pinion, two pulleys turning freely upon the shaft, gears on the pulleys, the said gears engaging with the pinions, means for driving one or both of the pulleys, and means for preventing rotation of one of the pulleys and means for preventing rotation of the shaft.

20. In a stop-motion, the combination with a shaft, a sleeve thereon and turning therewith, the said sleeve carrying a small and a large pinion, two pulleys journaled upon the shaft and turning freely thereon, one of said pulleys carrying a pinion engaging with the larger of the two pinions on the sleeve, and the other pulley carrying an internal gear engaging with the smaller of the pinions, means for driving one or both of the pulleys, and means for preventing rotation of one of the pulleys and means for preventing rotation of the shaft.

21. In a stop-motion, the combination with a driving-shaft, a cam moving in time therewith, means for positively rotating the shaft at the working speed, means for positively rotating the shaft at a slower speed, and means for stopping the shaft, the last two means being controlled by the movements of the cam.

22. In a stop-motion, the combination with a driven shaft, a cam moving in time therewith, means for rotating the shaft at the working speed, said means comprising two pulleys, gearing interposed between the pulleys and the shaft, a driving-belt, means for shifting the belt from one pulley to engage with both pulleys, and a positive stop for the

shaft, the said belt being shifted and the positive stop applied by mechanism controlled by the cam.

23. In a stop-motion, the combination 5 with a driven shaft and a cam moving in time therewith, of a sleeve carried by the driven belt, and carrying pinions, two pulleys loosely journaled upon the driven shaft, and carrying gears engaging with the pinions, a driving-belt, means for shifting the belt from one pulley so as to cause it to run upon both pulleys, a brake to prevent rotation of one of the pulleys, and a positive stop for the shaft, the said belt-shifting device, brake and 15 stop being actuated by mechanism controlled by the cam.

24. In a stop-motion, the combination with a driven shaft and a cam moving in time therewith, a sleeve upon the driven shaft carrying pinions, two pulleys loosely journaled upon the shaft and carrying gears which engage with the pinions, a driving-belt engaging with the pulleys, a belt-shifter for causing the belt to engage with one or both of the 25 pulleys, a brake for one of the pulleys, a positive stop for the shaft, a finger engaging with the cam, and mechanism controlled by the movements of the finger for actuating the belt-shifter, the brake and stop.

30 25. In a stop-motion, the combination with a driven shaft and a cam moving in time therewith, means for rotating the shaft, a projection on the shaft, a lever having a notch adapted to engage with the projection 35 and form a positive stop for the shaft, a finger connected to the lever, the end of the finger having steps, and a finger controlled by the cam and adapted to engage with each of the said steps.

40 26. In a stop-motion, the combination with a driven shaft and a cam rotating in time therewith, two pulleys adapted to drive the driven shaft at different rates of speed, a belt adapted to engage with one or both of 45 said pulleys, a belt-shifter, a finger connected to and controlling the movements of the belt-shifter, one end of the finger being stepped, and a second finger engaging with such stepped portion of the first finger and controlled by the cam and means for positively stopping the shaft.

55 27. In a stop-motion, the combination with a driven shaft and a cam rotating in time therewith, of two pulleys, gearing interposed between the pulleys and the shaft, a belt, means for causing the belt to engage with one or both of said pulleys to positively drive the shaft, the said means comprising a belt-shifter, a projection turning with the 60 shaft, a lever having a notch adapted to engage with the said projection and form a positive stop for the shaft, a finger connected to the lever, the ends of the said finger being stepped, connections between the finger and the belt-shifter, a second finger engaging with

the steps, and connections between the second finger and the cam for controlling the position of the former.

28. In a stop-motion, the combination 70 with a driven shaft and a cam rotating in time therewith, of two pulleys connected to the shaft, gearing between the pulleys and the shaft, and a belt adapted to engage with one or both of said pulleys to positively drive the shaft, a lever engaging with the belt for 75 the purpose of shifting it, the said lever having a slot, a pin engaging with the slot, a finger connected to the pin, the end of said finger being stepped, a second finger engaging with the stepped portion, and means actuated by the cam for moving the second finger and means for positively stopping the shaft.

29. In a stop-motion, the combination 80 with a driven shaft and a cam moving in time therewith, two pulleys on the shaft gearing 85 between the pulleys and the shaft, a belt adapted to engage with one or both of said pulleys to positively drive the shaft, a lever engaging with the belt and adapted to shift it, the said lever having a cam-slot, a projection on the shaft, a lever having a notch adapted to engage with the projection and form a positive stop for the shaft, a finger connected to the lever for the purpose of moving it, a pin connected to the finger and 90 engaging with the cam-slot, the face of said finger being stepped, a second finger engaging with the stepped portion and connections between the second finger and the cam.

30. In a stop-motion, the combination 95 with a shaft, two pulleys thereon, gearing between the pulleys and the shaft, and means for rotating one or both of said pulleys, a brake engaging with one of said pulleys and adapted to lock it against rotation, a projection on the shaft, and a lever having a notch adapted to engage with the projection and form a positive stop for the shaft, the said lever carrying means for applying the brake.

31. In a stop-motion, the combination 100 with a shaft and a pulley, a projection on the shaft, and a lever having a notch and adapted to engage with the projection, the said lever carrying means for applying the brake.

32. In a stop-motion, the combination 105 with a shaft, a pulley thereon, a brake for preventing rotation of the pulley, a member connected to the brake, and having a bent portion, a projection on the shaft, a lever having a notch adapted to engage with the projection, and a pin carried by the lever and adapted to engage with the bent portion of the member for applying the brake.

33. In a stop-motion, the combination 115 with a shaft, a cam rotating in time therewith, a projection on the shaft, a sleeve on the shaft rotating therewith and carrying a large and a small pinion, two pulleys loosely journaled on the shaft, one of said pulleys carrying a pinion engaging with the larger 120

130

pinion and the other of said pulleys carrying an internal gear engaging with the smaller of the two pinions, a belt adapted to engage with one or both of said pulleys and positively rotate the shaft, a lever having a notch adapted to engage with the projection on the shaft and form a positive stop for the shaft, a brake adapted to engage with one of said pulleys to prevent its rotation, a spring carried by the brake, the said spring having an angular extremity, a pin carried by the lever and adapted to engage with the spring for applying the brake, a lever engaging with the belt and adapted to shift it, the said lever having a cam-slot, a finger connected to and actuating the first lever, a pin

20 moved by said finger and engaging with the cam-slot on the belt-shifting lever, the free end of the said finger being stepped, a second finger carried by a shaft and engaging with the stepped portion of the first finger, a third finger engaging with the cam, means for disengaging the first finger from the second finger, and a spring for engaging the two fingers together.

25 This specification signed and witnessed this 25th day of May, 1905.
